Primary Examiner — Jasmine Mlinarcik
Assistant Examiner — James P McKane(57) CLAIM

The ornamental design for detachable pants as shown and described.

DESCRIPTION

FIG. 1 is a front view of a detachable pants shown in a detached position;

FIG. 2 is a rear view of the claimed design.

FIG. 3 is a left side view of the claimed design.

FIG. 4 is a right side view of the claimed design.

FIG. 5 is a top view of the claimed design.

FIG. 6 is a bottom view of the claimed design; and,

FIG. 7 is a perspective view of the detachable pants in an attached position.

The long dashed broken lines along the surfaces of the detachable pants depict stitching that forms no part of the claimed design.

1 Claim, 6 Drawing Sheets(56)
